UNITED STATES PATENT OFFICE.

SEBASTIAN G. BRINKMAN, OF TOWNS, NEW JERSEY.

PROCESS OF MAKING REFRIGERATORS.

Original application filed February 23, 1927, Serial No. 170,363. Divided and this application filed July 26, 1927. Serial No. 208,566.

This invention relates to improvements in refrigerators, and more particularly to a double or spaced wall porcelain refrigerator, and is a division of my application filed 5 Feb. 23, 1927, and bearing Serial Number 170,363, which has become Patent 1,667,281.

An object of the invention is to provide a refrigerator formed of a plurality of cooperating compartments, each compartment 10 being built with spaced porcelain walls, between which is a vacuum, or if desired, dead air may be trapped therebetween.

A further object of the invention is to provide suitable means and a novel process 15 whereby the spaced walled porcelain boxes or compartments may be molded and baked.

A still further object of the invention is to provide a process whereby the spaced walled porcelain compartments may be reinforced 20 and further provided with means whereby the usual refrigerator fittings may be supported.

Other objects will appear as the description proceeds.

25 In the accompanying drawings which form a part of my application,

Figure 1 is a perspective view of a refrigerator made in accordance with my invention;

30 Figure 2 is a sectional view taken on the line 2—2 of Figure 3;

Figure 3 is a sectional view taken on the line 3—3 of Figure 2;

Figure 4 is a front elevation of the outer 35 plaster mold;

Figure 5 is a vertical sectional view taken on a central line through Figure 6, and

Figure 6 is a sectional view taken on the line 6—6 of Figure 5.

40 Like characters of reference are used throughout the following specification and the accompanying drawings to designate corresponding parts.

In brief, I provide a porcelain refrigerator 45 composed of one or more integrally formed spaced walled compartments, which are sealed or closed by means of doors formed in the same manner and from the same material.

50 The refrigerator compartments 20 are formed in the following manner: A working table 1 is provided for supporting the mold and has an opening 2 cut through it near its central portion of a size corresponding to the largest outside diameter of the inner

mold. The core 3 is formed with four sides and a top, and is open at its bottom. The lower portion of the inner core 3 is outwardly flared as at 4, to provide for the bevel usually found in the front of refrigerator compartments, and cooperates with a correspondingly beveled surface of a door, to form a tight joint. It will be seen that the core 3 is 60 slideable within the opening 2, and is supported by the table in any suitable manner. The top of the core 3 is closed except for a central opening 5, the sides of which are beveled and cooperate with the beveled sides of a central supporting head 6, carried by the adjustable standard 7. It will be understood that all parts of the core 3 and head 6 65 are formed of plaster.

A recessed base plate 8 of plaster is positioned about the core 3, and seats on the annular flange about the lower edge of said 75 core. The plate 8 is supported on the table 1, and supports the mold 9 in spaced relation to the core 3. The mold 9 comprises four interlocking walls of plaster and is provided with an interlocking removable top 10. 80 When the base plate, core and mold are in position, the several joints between the same are sealed with clay to prevent leakage of the slip when poured in the mold. A filling tube or pipe 11 of brass extends into the 85 space between the core and mold, while an overflow pipe 12 also extends through the upper portion of the mold 9 to let the air out of the mold and to give warning when the mold is completely filled with the clay slip. 90 A drain pipe 13 extends upward into the space between the core 3 and mold 9, and is used to drain off the undesired portion of the clay slip, after the walls of the compartment being molded have been formed to the 95 desired thickness. This operation is usually calculated by time, since the plaster between the core and mold absorbs the moisture in the clay slip, and causes a wall to be built up against the sides thereof. Each compartment will be formed with at least one side wall 60 of a single thickness, which will be arranged with a surrounding peripheral flange 65, so that when the compartments are in place, one above the other, or side by 100 side, there will be a space provided therebetween for trapped air.

Plugs 14 extend through the core 3, towards the inner wall of the mold 9, and provide passages 15 in the refrigerator com- 110

partments, for the passage of air through the same, or through adjacent compartments. The plugs 14 being made of plaster, will also cause the clay slip to form a wall about the same. Likewise the spaced walls of the compartments will be reinforced, by inserting plaster plugs 16 through the core 3, and permitting the clay slip to build up around the same. Plugs 17 will be inserted through the core 3 to form openings in the inner wall or surface of the compartments to receive supporting means for the trays 18. The compartments will be so formed that the passages 15 are in alinement with similar passages in adjacent compartments, so that a circulation of air may be had between the several compartments of the refrigerator.

Assuming that the core and mold are in position, the method of making the compartments is as follows: The space between the core and mold is completely filled with a clay slip, through a funnel in the filling pipe, until the slip starts to run out of the overflow pipe 12, at which time the overflow pipe is closed by means of a suitable plug. The funnel will be kept full of the slip. The slip is permitted to set for approximately four hours, during which time, the moisture will be drawn out into the plaster walls of the core and mold, and spaced walls will be built up from the slip. A drain plug in the drain pipe 13 is then removed and all of the slip remaining in liquid form will be drained from the mold. At the same time an air line will be connected to the filling pipe and a low pressure of air will be directed into the space between the walls formed by the slip. In this manner the upper or outer wall formed by the slip will be supported on an air cushion, and will be kept from collapsing. In place of the air cushion, it is found that water or any suitable fluid can be substituted in lieu thereof. After this operation, the core is lowered through the central opening in the table, while the supporting head is held in its raised position to support the inner horizontal wall formed by the slip. After a predetermined length of time the air may be turned off, or the water drained from the space between the walls, and the supporting head lowered through the opening in the table, and the mold taken apart. It will thus be seen that a spaced walled compartment having reinforced walls, will be formed. The refrigerator fittings may be applied in any suitable manner. The doors for the compartments will be formed in the same manner, but with different molds. The

compartment walls will be approximately one half inch in thickness, while the space therebetween will also be approximately one half inch. The box or compartment will usually be fired in a kiln while in a biscuit state, after which a plurality of glazing coats will be applied to the box, which will then be burned a second time in a gloss kiln, to form the completed article. However, one firing may be used instead of two firings.

The space between the walls of the compartment may be filled with dead air, or may be a vacuum, as desired.

If several compartments are to be used together to make a refrigerator, suitable bolts 19 may be employed to hold the said compartments in place. The compartments may be supported directly on the floor, or on a base 21.

From Figure 2 of the drawings, it will be apparent that the compartment on the upper right hand corner will be the ice compartment, and that the cold air will pass down through the passage into the lower right hand compartment, and from there to the lower left hand compartment, and up into the upper left hand compartment, and finally back into the upper right hand compartment. Hence, a complete circulation of air in the several compartments will be had, thereby keeping the temperature in the several compartments at a fairly even degree. It will be apparent that no insulating material will be used as in the ordinary form of refrigerators, and the vacuum or dead air between the spaced walls will serve to retain the cold within the compartments. Of course, the compartments could be used just as successfully as a medium for heating, as the double spaced wall construction renders the compartments thoroughly air tight and insulated.

Many minor changes in detail of construction may be resorted to without departure from the spirit of the invention.

Having thus described my invention what I claim as new and desire to secure by Letters Patent of the United States is:

The process of forming an integral molded spaced double walled porcelain refrigerator unit, consisting of setting plaster forms in spaced relation, pouring a clay slip therein, permitting the same to set for a period of time, draining the excess slip, admitting low pressure of fluid between the walls formed of the slip, and mechanically supporting the inner top wall of the unit.

In testimony whereof I affix my signature.
SEBASTIAN G. BRINKMAN.
